METHOD OF CONTROLLING WELLS

Ira A. Miller, Dallas, Tex., assignor to Otis Pressure Control, Inc., Dallas, Tex., a corporation of Texas

Application May 16, 1949, Serial No. 93,509

8 Claims. (Cl. 166—21)

1

This invention relates to the method of controlling petroleum wells and refers more particularly to shutting off the flow of wells temporarily by closing off well conduits other than by the usual flow control equipment of the well. This is oftentimes required in order to close off a well to permit a modification of the control equipment as, for instance, for the purpose of repairing, replacing or installing different flow equipment.

It has heretofore been proposed to close off or freeze off conduits extending substantially horizontally by injecting therein a slurry or slush of small ice particles and water and then externally refrigerating the conduit whereby the slush is turned into a plug of ice which effectively closes off the conduit. However, when it was attempted to close off the flow string or other pipe string of a petroleum well by this method, it was found that the ice slurry usually fell through the pipe string too quickly for it to freeze due to the pipes' vertical position, rendering it impossible to form an ice plug within the pipe string.

An object of this invention is to provide a method for controlling a petroleum well under pressure by closing off the string well conduit to be controlled other than by the usual control equipment of the well.

Another object is to provide a method of controlling a well producing substances which are not readily freezable at temperatures near the freezing point of water by injecting viscous cohesive material into the conduit to be controlled to form a static plug therein and freezing this material.

A further object is to provide a method for closing off a well conduit other than by the usual well control equipment where the conduit has a larger diameter than any connection communicating therewith.

Still another object is to provide a method of modifying the control equipment of a well by temporarily closing off the well conduit to be controlled below the lowest operable control therefor whereby the desired modification of the control equipment can be made.

Other and further objects of the invention will appear from its description.

In the accompanying drawings which form a part of the instant specification, are to be read in conjunction therewith, the single figure is an elevational view partially in section of well head and flow control equipment illustrating a method of closing off one of the well conduits in accordance with an embodiment of this invention.

It is believed that the invention will be more

2

readily understood by first referring to the structural parts of a typical well head installation. Referring to the figure, the ground surface is shown schematically at 5 having a bore hole 6 extending vertically therein. Within the bore hole is set the usual well string of casing 7, and in the interest of simplicity, other surface strings of casing have been omitted from the drawings.

Supported on the casing string 7 is a Christmas tree designated generally by the numeral 8 equipped with the usual flow connections 9 communicating through the control equipment with the interior of the flow string of pipe or tubing 10.

This Christmas tree or control equipment includes the casing head 11, a ram type tubing head 12 and master valve 13. It is to be understood that this control equipment is shown by way of illustration and not in a limiting sense but that the invention may be employed regardless of the type or kind of control equipment with which the well is equipped.

The tubing head 12 serves a double purpose, providing a hanging means for suspending the tubing string 10 and also providing a means for sealing the annulus between the body of the tubing head and the peripheral wall of the tubing string. The means for accomplishing this includes opposing rams 13 carrying packing elements 14. The packing elements are made up of suitable seal material and with the two rams forced into engagement with the wall of the tubing by the rods 15, and with each other, provide a seal between the rams and the tubing. Seal elements 16, in the upper surface of the rams, provide the seal between the rams and the tubing head body. The rams are mounted for sliding movement in the cylindrical portions 12a of the tubing head and their position therein is controlled by the usual rods 15 which have a threaded connection within the bonnet 17 bolted to the tubing head body. Of course, the hanging function is provided by the engagement of the tubing collar 10a on the upper surface of the rams.

The rams may be withdrawn from the tubing head for the purpose of repair or replacement of packing by removing the bolted bonnet 17. These rams are all in accordance with well known commercial equipment, and it is believed that additional description thereof may be dispensed with.

The invention may be employed with utility under many varied conditions. By way of illustration, a few examples of conditions which make it advisable to close off a well string of pipe to permit modification of the flow control

equipment will be given. Oftentimes upon occurrence of the first signs of blowing, well equipment will be installed which is not adapted to control the pressures which develop in the well but which is installed because of its ready availability at the time the well comes in. It then becomes necessary to close off the well in order to modify the control equipment to install equipment which is heavy enough to control the pressures that develop in the well.

Oftentimes when working on producing wells, the bolts holding down the control equipment mounted on the tubing hanger are removed in order that the packing or other parts thereof may be repaired. Sometimes when this occurs, if the blowout preventers or rams of a ram type head are not sufficient to hold the tubing string against the pressure within the well, the whole tubing string, including the well head equipment secured thereto, will be forced upwardly, sometimes even looping over due to the weight of the Christmas tree. This, of course, is not a usual occurrence but is a problem with which the industry is occasionally presented. When this does occur, it is necessary to close off the tubing below the loop and adjacent the well head so it may be cut and threaded to receive a new tubing length and then equipped with suitable control equipment. This invention is well adapted for this use.

Other operations for which this invention is especially adaptable include the replacement of all or certain lengths of the well tubing which may be corroded or eroded, the repair or replacement of certain portions of the well control equipment including packing and seal elements, and the removal of tools, pipe strings or the like that might have become jammed within one of the well conduits while it was being lowered into the conduit and wherein the jammed equipment, a lowering line, rod or the like, extending through the control equipment makes it impossible to operate the usual normal control equipment.

In accordance with this invention, when it is desired to shut off the flow through a well conduit and where the conduit to be closed is filled with a substance such as petroleum oil or gas, which is not readily freezable at such temperatures that may be easily obtained by available sources of refrigeration, a substance which is readily freezable at or near the freezing point of water is forced into the conduit at the zone it is to be closed off to form a static plug which may then be frozen by application of refrigeration exteriorly of the conduit. It has been found that this refrigeration may be adequately and suitably provided by placing a pack of Dry Ice about the exterior of the conduit at the level it is to be frozen off. It is usually desirable to carry out this operation in one of the flow fittings which make up a part of the conduit for the reason that this portion of the conduit has an irregular inner surface due to the presence of shoulders, constrictions, lateral flow connections and the like. The plug of material, when frozen within the wall of such irregular contour, is firmly held in place by the irregularities to better withstand the pressure differential thereacross when the conduit, downstream from the plug, is opened while carrying out the modification operation. However, it has been found that a conduit having substantially cylindrical walls as, for instance, in a length of tubing, can be closed in accordance with this invention.

It has been found to be necessary for the plug to be substantially completely static during the actual freezing operation.

In some instances, water has been successfully employed for this purpose, even in vertical conduits, where the pressures to be controlled are very high as, for instance, five thousand pounds per square inch and higher. It is not understood what causes the water to remain in the upper portion of the conduit and resist gravity, but it is assumed that the very high pressures involved serve to hold the water in place at the upper portion of the conduit though the conduit is filled with a lighter substance, such as gas, below the water level. However, it has been found that when lower pressures are involved, the water rarely, if ever, will remain in place as a static plug so that the freezing may proceed, and that oftentimes, even in high pressure wells, the water will flow to the bottom of the tubing.

Because of the uncertainty of the results to be obtained when it is attempted to use water as the substance to be injected into the conduit, it is not recommended that water be used for this purpose. This is especially true where the situation is one in which time is of the essence. In order to avoid a blowout, the use of water should not be risked because of the likelihood of failure of the water to remain as a static plug which may be frozen in the upper portion of the conduit.

It has been found that a plug of frozen material can be obtained in every instance where a viscous cohesive material is forced into the conduit in the refrigerated zone. The consistency of the substance should be such that it is self-supporting in the sense that molding clay is self-supporting when suspended as a bar when supported at its upper end. When a conduit is of small diameter, that is, having an internal diameter of about that of the usual flow tubing, the substance may be somewhat more fluid than where larger diameter conduits are involved. For larger diameter conduits, the material should be very viscous and cohesive.

It has been found that mixtures of earthen materials and water are entirely satisfactory for this purpose. These earthen materials may be naturally occurring dirt or clay in the vicinity of the well where these are not sandy, or may be clays which are commercially prepared and sold for use in drilling muds. It is preferable to use material having abrasive substances therein such as shell, rock particles or the like because these abrasives frictionally engage the walls of the conduit to hold the plug of the substance more securely within the conduit both while the plug is being frozen and after it is frozen.

Where the material may be introduced into the frozen zone of the conduit to be closed through a flow passage which is no smaller than the diameter of the conduit of the refrigerated zone, it may enter the conduit axially thereof. However, where large diameter conduits such as well casings are to be closed off, it is usually necessary to introduce the material into the conduit through a relatively small opening as, for example, a two inch diameter flow fitting of a casing head. Obviously, a rod of cohesive material having a diameter of approximately two inches will fall downwardly within the large diameter conduit and therefore, the material is preferably extruded into the conduit at an angle to the longitudinal axis of the conduit. When this

is done, apparently the material as it extrudes into the conduit is caused to engage the walls of the conduit and to adhere thereto. As additional material is forced into the conduit, a plug is finally built up which will close off the interior of the conduit. When the material is introduced directly into the refrigerated zone of the conduit, engagement of the moist extruded ribbon with the refrigerated wall causes the material to freeze to the wall and aid in the formation of a static plug of material. Therefore, it is usually preferable to refrigerate the conduit before the substance to be frozen is introduced into the conduit, but sometimes the refrigeration may be applied after the plug of freezable substance has been formed within the conduit.

It is believed that an understanding of the invention will be facilitated by referring to a specific example and attention is directed to the drawings for this purpose. It will be assumed for purposes of this explanation that the packing element 14 of the ram type tubing head has become worn and must be replaced. The ram and packing element may be withdrawn from the tubing head by removing the bonnet 17, but before this can be done, it is necessary to close off the annulus between the conduit provided by the casing 7, the casing head 11, and the tubing head 12 and the conduit provided by the string of flow tubing 10. Also, it is necessary to close off the interior of tubing 10 and to suspend the tubing for it will be recalled that the rams serve the dual function of suspending the tubing and providing a seal between the tubing and the tubing head.

In accordance with this invention, the conduit, including the casing 7, may be closed off by forcing a plug of viscous cohesive material into the space between the tubing and the casing head. Refrigeration is applied to the exterior of this conduit by means of a Dry Ice pack 18 supported exteriorly of casing head 11 by a retainer 19 secured to the upper end of casing 7. When a static plug of viscous cohesive freezable material has been formed within the casing head closing off the annulus, the refrigeration provided by the Dry Ice pack will freeze the plug to effectively seal off the annulus.

The flow fitting 11a of the casing head is equipped with a valved fitting 20 and to this fitting is secured a cylindrical member 21 which may be, for instance, a length of five inch casing. This barrel or cylinder 21 is filled with cohesive earthen balls 22 which are a mixture of earthen material and sufficient water to make them moldable and cohesive. A plug 23, substantially filling the interior of barrel 21, backs up the balls 22 and will serve as a piston for forcing the cohesive substance of the balls 22 into the interior of the conduit to be closed off.

A driving force for extruding the cohesive material into well head 11 may be provided by securing a cap 24 onto the free end of barrel 21. The cap has an aperture therethrough connected by line 25 with a source of fluid pressure which may be the discharge of a pump 26 or may be a connection to a high pressure gas or the like.

Around the usual well installation, there usually are numerous pumps which may be employed for actuating the piston 23. Examples of these are pumps for forcing cement into a well during cementing operations, slush pumps for circulating drilling mud, pumps for actuating blow-out preventers and the like.

When the Dry Ice pack 18 has been secured 75 in part, from the interior of the casing head

about the well head, the barrel 21 secured to connection 20 and filled with balls 22 and then connected with the source of fluid pressure, valve 20 is opened and the substance of the balls 22 is extruded through the opening 11a into the interior of the casing head. Just what happens within the casing head, of course, is speculative, and the theory advanced here is given by way of explanation and is not to be considered as binding or limiting the scope of the appended claims or of the invention.

It is believed that the ribbon of material 22a, as it extrudes from the opening 11a, enters the annulus and due to its stiff and cohesive character, will extend substantially laterally into the interior of the conduit until it engages a rigid surface such as the wall of tubing 10 or the inner wall of the well head. It will then commence to loop over in a distorted manner in a fashion similar to toothpaste squeezed from a tube. The material 22 is forced by high pressure into the well head and finally forms a static plug of material closing off the annulus between the tubing and the well head. When sufficient material has been forced into the conduit to provide the static plug, valve 20 is closed and sufficient time is allowed for the plug to freeze solidly. Of course, during the freezing of the plug, the material expands so as to tightly fill the annulus and effectively seal it off. It will be noted that the inner wall of the casing head is somewhat constricted adjacent the lateral openings 11a and it will be appreciated that the plug of material frozen within the annulus will be additionally secured in place due to this irregular contour and also due to portions of frozen material extending into the lateral openings 11a.

It is contemplated that the static plug may be formed within the conduit prior to refrigeration, but where large diameter conduits are involved, it is preferred to refrigerate during the formation of the plug.

When the annulus has been sealed off, the interior of the tubing 10 may be closed off in a conventional manner well known to those skilled in the art, by lowering a plug into the interior of the tubing and anchoring it in place adjacent the upper end. This is done with the use of special equipment, now in commercial use in the oil industry, and not constituting in itself a part of the invention, and for this reason, further reference to such equipment will be dispensed with in this instrument.

A spear is then lowered through the upper control equipment and engages the upper end of tubing 10, also in a manner which is commercially carried out in the oil fields, and which spear is connected to the usual derrick or mast through a traveling block or the like and serves to suspend the tubing string so that the ram 13 may be withdrawn from the tubing head in order that the packing element 14 may be replaced.

As heretofore indicated, the bonnet 17 is removed to permit withdrawal of ram 13. When the packing element 14 has been replaced in the ram and any other necessary repairs made, the ram is reinserted into the tubing head, the balance secured in place and then the spear which suspended the tubing is removed as is the plug which was previously landed to close off the interior of the tubing. The upper flow control equipment above the tubing head 12 is placed in proper order and then the plug of frozen material is allowed to thaw and may be extruded, at least

through outlets 11a by the pressure within the annulus.

In an operation such as this, it usually is not necessary to thoroughly clean out the substance 22a when the modification operation is completed, but in instances where this is desirable, as where well products are produced through the annulus, the material may be washed from the conduit closed off in any suitable manner which will be well understood to those skilled in the art.

From the foregoing it will be seen that this invention is one well adapted to attain all of the ends and objects hereinabove set forth, together with other advantages which are obvious and which are inherent to the method.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. The method of temporarily closing off a vertically disposed well conduit other than by the usual flow control equipment where the conduit contains substances not readily frozen at temperatures near the freezing point of water comprising the steps of applying refrigeration to the exterior of the conduit at the position or level thereof that it is desired to close it off, and while continuing the application of refrigeration to the conduit injecting into the conduit a viscous cohesive substance readily freezable at the temperature of refrigeration of the conduit to form a static plug of the cohesive substance in the refrigerated zone, and continuing the refrigeration to freeze a plug of solid material within and closing off the conduit.

2. The method of temporarily closing off a vertically disposed well conduit other than by the usual flow control equipment where the conduit contains substances not readily frozen at temperatures near the freezing point of water comprising the steps of applying a pack of Dry Ice about the exterior of the conduit at the level it is desired to close off the conduit in a manner to refrigerate the interior thereof, and while continuing the application of refrigeration to the conduit injecting into the conduit a viscous cohesive substance readily freezable at the temperature of refrigeration of the conduit to form a static plug of the cohesive substance in the refrigerated zone, and continuing the refrigeration to freeze a plug of solid material within and closing off the conduit.

3. The method of temporarily closing off a vertically disposed well conduit other than by the usual flow control equipment where the conduit contains substances not readily frozen at tem-

peratures near the freezing point of water comprising the steps of applying refrigeration to the exterior of the conduit at the position or level thereof that it is desired to close it off, and while continuing the application of refrigeration to the conduit injecting a viscous cohesive mixture of water and earthen material into the interior of the conduit at the refrigerated zone to form a static plug of the cohesive substance therein, said mixture having a consistency similar to that of molding clay, and continuing the refrigeration to freeze the cohesive substance to a plug of solid material within and closing off the well conduit.

4. The method of claim 3 wherein the earthen mixture contains abrasive material.

5. The method of claim 3 wherein the refrigeration is provided by securing a Dry Ice pack to the exterior of the conduit at the level it is to be closed off.

6. The method of temporarily closing off a vertically disposed large diameter well conduit other than by the usual flow control equipment of a well where the conduit is filled with a material not readily frozen at normally available refrigeration temperatures comprising the steps of refrigerating the well conduit at the level it is desired to close it off, extruding a viscous cohesive self-supporting substance laterally into the refrigerated zone through an opening of smaller diameter than the conduit to be closed to form a static plug of cohesive substance therein, said substance being readily frozen at the available refrigeration temperatures within the conduit and continuing the refrigeration to form a frozen plug of the cohesive substance to close off the well conduit.

7. The method of claim 6 wherein the material to be frozen is a water earthen material mixture of about the consistency of molding clay.

8. The method of modifying the control equipment of a high pressure petroleum producing well having a well conduit operatively connected to and controlled by the control equipment comprising the steps of forcing an earthen mixture containing sufficient water to render the mixture deformable and cohesive into the conduit at the level it is desired to close the conduit off to form a static plug of the mixture therein, applying refrigeration to the exterior of the conduit at the level of the plug to freeze the plug solidly closing off the conduit, then modifying the control equipment located above the frozen plug as desired while maintaining the frozen plug, and then thawing the frozen plug.
